UNITED STATES PATENT OFFICE.

HORACE R. ALLEN, OF INDIANAPOLIS, INDIANA.

POR TABLE BATH-TUB.

SPECIFICATION forming part of Letters Patent No. 320,037, dated June 16, 1885.

Application filed July 30, 1884. (No model.)

To all whom it may concern:

Be it known that I, HORACE R. ALLEN, a citizen of the United States, residing at Indianapolis, in the county of Marion and State of Indiana, have invented certain new and useful Improvements in Portable Bath-Tubs, of which the following is a specification, reference being had therein to the accompanying drawings.

My invention relates to a portable bathing apparatus; and it consists in the construction, arrangement, and adaptation of the parts, as will be more fully hereinafter set forth, and specifically pointed out in the claims.

In suburban and rural districts the residences are ordinarily without water supplied under force, and to form a reservoir at a greater height than the building would constitute an item of no inconsiderable expense; hence force-pumps and connections to a cistern or other water supply are ordinarily used.

A bathing apparatus with means for varying the temperature of the water is not only a necessary adjunct to good sanitary hygiene, but a luxury. To provide such means with peculiar adaptability to the purpose is the object of this invention.

I will describe my invention arranged to employ naphtha or other hydrocarbon oil as a heating fuel; but it is apparent that gas may be employed without departing from the principle of the same or sacrificing its advantages.

In what I consider the best way of carrying out the invention I employ the mechanism illustrated in the accompanying drawings, which form a part of this specification, and in which—

Figure 1 is a perspective view of a portable bath-tub with my improvements applied thereto. Fig. 2 is a longitudinal section of the same.

Referring to the drawings, A designates the bath-tub proper, which is of any ordinary and approved form and material, and it is provided with a support or supports, as B, for removable burners C. These burners C are supplied with fuel from a reservoir, C', by a pipe, c, and these parts may be of any suitable construction. Downwardly-projecting flanges a retain the products of combustion upon the bottom of the tub and direct them to a chute, a', which is formed upon the inclined end of the tub. These flanges and chute form an important adjunct to the tub, as they compel the

heated products of combustion to bathe the lower surface of the tub, and the soot and smoke to collect on the surfaces instead of the sides 55 of the tub or escape into the apartment. The tub is provided with pockets for soap, sponge, flesh-brush, &c., and has secured to one end a waste-basin, D, a passage, d, connecting the two, and having a controlling plug, as d'. From 60 the lower portion of this waste-basin D is projected a coupling, D', to which may be attached at will a flexible waste-pipe, D''. A pump, E, is secured to the tub, or forms a part thereof, and this pump has peculiar adaptation for service in relation to the tub, the cistern-connection, the waste-basin, and a showering apparatus, G. This showering device G is rigid with or removably secured to the tub, so that the showerer will be suspended above the tub, 70 and is connected by a pipe, g, to the body F of the pump E above the valves. The pump is preferably double acting, and is located adjacent to the waste-basin. It has a supply-connection, f, with the interior of the tub, controlled by a rubber plug, f', and a supply-connection with the flexible pipe H. This flexible pipe H has means for coupling it with a pipe-connection which leads to the cistern, and this pipe is of four-ply hose, which will protect from freezing. The pump has a spout, e, which empties into the tub, and this spout is controlled by a stop cock, e', as shown. If the pump is operated with the plug f' away from its seat and the cock e' closed, the effect is to 80 throw the contents of the tub into the showering attachment, as the force of the pump acts upon the nearest source of water. If the plug f' is in position and the cock e' closed, it will force the cold water from the cistern to the showerer. If the cock e' is open, it will force the water from the cistern into the tub, because the water will seek the nearest outlet, hence it will be seen that the operator can readily pump water from the cistern into the tub or the showerer, or from the tub into the showerer, or into parts or vessels, as may be desired.

I am aware that portable bath-tubs have been before proposed, and that furnaces for heating tubs and vats have been made integral with the structure thereof. Such features are not sought to be covered, broadly, in this application.

What I deem to be important in this appli-

cation is, first, the portable bath-tub having means for supporting removable heating-burners, and also for controlling and directing the products of combustion; second, the portable bath-tub having the described pump connections.

Having thus described my invention, what I claim as new, and desire to secure by Letters Patent, is—

- 10 1. A portable bath-tub having supports, as B, flanges, as a , and a chute, as a' , constructed and adapted to serve as set forth, combined with removable heating apparatus, as C, and with means for forcing and draining water, as 15 and for the purposes described.
2. A bath-tub having an outside basin secured thereto, an opening communicating with

said basin, and the tub closed by a removable plug, in combination with a pump having branch pipes communicating with the tub, the 20 fresh-water supply and showerer, and with a flexible drain-pipe opening into said basin, substantially as and for the purposes set forth.

3. The pump E, having connections g and f , as described, and having spout e , with cock e' , combined with the flexible pipe H, the showering device G, tub A, and plug f' , as and for the purposes set forth.

In testimony whereof I affix my signature in presence of two witnesses.

HORACE R. ALLEN.
